UNITED STATES PATENT OFFICE.

JOHN VALENTIN STENGER, OF FROHNLEITEN, STYRIA, AUSTRIA-HUNGARY, ASSIGNOR TO THE MASCHINENBAUANSTALT GOLZERN, (VORMALS GOTTSCHALD & NÖTZLI,) OF GOLZERN, GERMANY.

PAPER-MAKING MACHINE.

SPECIFICATION forming part of Letters Patent No. 296,083, dated April 1, 1884.

Application filed January 31, 1884. (No model.) Patented in Austria-Hungary August 30, 1881, No. 17,265 and No. 31,172, and in Germany January 13, 1882, No. 19,193.

To all whom it may concern:

Be it known that I, JOHN VALENTIN STENGER, of Fronleiten, in the Duchy of Styria and Empire of Austria, have invented a new and useful Improvement in Paper-Making Machines; and the following is declared to be a description of the same.

This invention refers to that kind of paper-making machines heretofore employed in which a band of wire fabric has passed around cylinders, and a cylinder has been covered at its circumference with both a coarse under wire and a fine top wire, and revolves in a vat filled with pulp and water, and in which machines the sheet of wet pulp is deposited on the fine top wire on the surface of the cylinder.

The object of the present invention is to obviate the difficulties experienced in the aforementioned paper-making machines, and to combine their advantages in one machine, employing both a cylinder covered with wire cloth or fabric and an endless web of fine wire-cloth passing over said cylinder and over other cylinders at the place of delivery of the sheet of paper-pulp; and I also use in my improved machine cylinders or bands of thin rubber passing around the ends of the wire-cloth cylinder and between the circumference of coarse wire and the web of fine wire, and these bands, preventing the water passing through the wire fabrics into the cylinder, limit the width of the sheet of paper-pulp. I also use improved buckets for supplying the paper-pulp and water to the machine, and improved mechanism for operating said buckets.

In the drawings, Figure 1 is a plan with portions of the upper parts removed, and Fig. 2 is an elevation of the machine.

Above the pulp vat or chest E, in which the cylinder A revolves, I arrange a series of suitable bearings for the reception of wire leading-rollers a b c d e f. The cylinder A is covered with a coarse-wire fabric, instead of its usual fine-wire-fabric cover, and I use a long belt or web of wire fabric, S, which passes over the cylinder A and rollers a b c d

e, the roller f being placed in its proper bearings externally after the wire belt S has been put in place. The rollers d and e regulate the tension of said wire belt S, both rollers being provided for this purpose with supports or bearings 1 and 2, adjustable by screws. The power to drive the belt S may be applied to either of these rollers. The long fine-wire belt S performs the function of the removed fine cylinder-wire, inasmuch as the said wire belt S, if the machine is started, is made to travel or revolve, as well as the cylinder A and rollers a to f, by means of the wet felt belt F, which receives its revolving or traveling motion by press-roller W.

The cylinder A, which in the former cylinder-machine was loaded by the couch and felt roller B, is in the present machine provided with bearings, which are kept down by set-screws H, which prevent any rising of the cylinder A by means of the tight wire belt S in its revolving travel. The couch and felt roller B, instead of bearing on the surface of cylinder A, is now carried by the long wire belt S and by the roller c, which latter replaces the lower couch press-roller of other machines. The wet sheet of paper-pulp P, formed on the long fine-wire belt by the evacuation of water into the cylinder A, is pressed between the two rollers B C and between felt F and long wire S. The wet sheet of paper-pulp is taken up by the felt F from the long wire belt S, and is automatically carried onto the press-rollers W W'. The couch-press B C may be weighted at will by weights G, and may be shifted, together with the wet felt F, by means of the adjustable bearings L L', into the most suitable position, according to the requirements of the paper to be manufactured. By this new arrangement of the long wire belt S ascending with the wet sheet of paper-pulp up to the roller b, and of the couch-press B C, working with a gradual pressure upon the felt, the sheet of pulp, without the employment of any suction apparatus or vacuum-box, is deprived of water to such an extent that no displacing in the first press W W' will take place at the

highest pressure, and even if these press-rollers work without any felt covers or manchons. Therefore it is possible not only to manufacture the thinnest paper at high speed, but also 5 to produce thickest card-board in double quantity of first-rate quality.

This machine possesses the eminent advantage of conducting the wet sheet of paper-pulp from the couch-press to the first press 10 without requiring for this any special kind of wet felt.

The machine may be employed with equal success for making paper or for drying or desiccating wood pulp.

15 The width of the sheet of paper-pulp is regulated and effected in this machine neither by the cover-strap, as in long-wire paper-machines, nor by covering the top wire, as in cylinder paper-machines, but simply by end-20 less and very thin india-rubber bands or straps, which are stretched around the circumference of the cylinder at the ends. These bands or straps are tightly laid around the coarse wire of the cylinder A in any required width, and 25 intervene between the wire cylinder and the wire band. These bands limit the width of the paper by preventing the pulp-water passing through the wire band S, and the pulp will not deposit upon the wire band, except where 30 the water runs freely through the wire belt. The india-rubber straps do not interfere with the revolving long wire belt S, but form a bed or layer for the same on the cylinder A. The 35 india-rubber may be placed within the wire of the cylinder, and the cylinder is made to revolve by the traveling belt S, or otherwise, as desired. These straps or bands, pressed between the long wire belt S and the cylinder A, or its under wire, prevent any paper-pulp 40 forming upon the belt S, and also prevent water entering into the cylinder A through them or at the place where they are applied. The packing between the vat or chest and cylinder remains unchanged, so that no loss in pulp 45 may occur.

The water-spout or spray-pipe *g* extends the entire width of the cylinder A, between this cylinder and the long wire belt S. The pipe *g* effects a double purpose. The water-spray 50 falling removes all pulp from the lower coarse wire around cylinder A between the rubber straps or bands. A portion of this water falls upon and running down the elastic bands arrives at the angle formed at P' by the cylinder 55 A and the long wire belt S, and percolates through the long wire belt S in a direction opposite to the water, which passes from the pulp into the interior of the cylinder, thereby removing all superfluous pulp from the long 60 wire belt S beyond the width of the sheet, as determined by said rubber bands. The alteration of paper-width is easily and quickly accomplished by putting on elastic bands of different width. The water from a second 65 water-pipe, *i*, is discharged downwardly, and removes all waste pulp from the wire belt S du-

ring its travel from the roller *e* to roller *f* by ejecting the water against the inside of this wire and through to the outside. By this arrangement the undisturbed continuous formation of an endless paper sheet is secured. 70

A further improvement consists in the regulating device for the uniform admission of the paper-pulp and for uniform dilution of the pulp by the spent or waste water. The disk, with 75 its connecting-rod *n*, causes two buckets, C and D, to make a vertical up-and-down movement, and a tilting motion is imparted to the two buckets at their highest point of vertical movement. Bucket C is for the paper-pulp, which 80 enters from the pulp-chest Z by pipe *h*. Bucket D is for the diluting return-water, which enters by pipe K from the cylinder A. Each bucket has a side wall, *l*, adjustable in height by addition or removal of small bars, and a 85 valve in the bottom to admit pulp or water. Each bucket is provided with two projecting pins, *m*, traveling between guides *v v*. The connecting-rod *n*, attached to the pins *w*, will lift the buckets in a vertical direction until the 90 pins *m* strike against the closed end of guides *v*. The connecting-rod *n*, continuing its upward stroke, will cause the buckets to tilt, the pins *m* serving as pivots for this tilting motion, and the contents of the buckets will be emptied into the gutter O at the lowest point of stroke 95 of connecting-rod *n*. The buckets C D are below the level of pulp or water, and the buckets therefore, in being raised above the level, are filled up to the upper edge of their side 100 wall, *l*, which upper edge is made adjustable. The bucket therefore will only lift and empty into gutter O by the tilting motion such quantity of pulp or water as is required for the paper and proper working of the machine. With 105 this regulating device there is no formation of foam or froth, which is so annoying with scoop-wheels, the buckets working quietly at about ten strokes per minute. The diluted pulp is conducted by the gutter O into the cylindrical 110 knotter R by the small gutter O', and enters from this knotter into the vat or chest E of the cylinder A, where the formation of paper takes place.

The presses and drying apparatus necessarily connected with this paper-making machine may be constructed according to any well-known devices.

I claim as my invention—

1. In a paper-making machine, the combination of the cylinder A, a coarse-wire covering, and rubber bands or straps upon the same, and the belt of fine-wire fabric S, substantially as set forth.

2. In a paper-making machine, the combination, with the cylinder A and belt of felt F, of the belt of fine-wire fabric S, the rollers *a b f*, the rollers *d e* and their screws, for regulating the tension upon the wire fabric S, and the rollers B C, between which the web of paper-pulp is pressed before passing off upon the felt fabric, substantially as specified. 125 130

3. The rubber bands or straps upon the cylinder A, in combination with the coarse-wire covering to said cylinder A, and the belt of fine-wire cloth S, whereby the width of the deposited web of paper-pulp is regulated, as set forth.

4. In a machine for making paper, the combination, with the cylinder A, belt of wire fabric S, and rollers around which said belt passes, of the rubber bands upon the cylinder A, and the water-pipes *g i*, whereby water is discharged downward, the water from pipe *g* cleansing the coarse-wire covering upon cylinder A and washing away surplus paper-pulp opposite to the rubber bands, and the water from pipe *i* cleansing the fine-wire belt on its return movement, substantially as specified.

15 5. The vats for holding paper-pulp and wa-

ter, and the vat L and pipe K, in combination with the pair of buckets C D, a connecting-rod, ²⁰ *n*, for lifting said buckets, a pin and slide, V, for tilting the same and discharging the pulp and water, substantially as specified.

6. The buckets C D, constructed with side walls, *l*, adjustable in height by small removable bars, whereby the quantity of pulp and water to be raised at each upward movement is regulated, substantially as set forth.

In testimony whereof I have hereunto set my hand, this 29th day of October, 1883, in the ²⁵ ³⁰ presence of two subscribing witnesses.

JOHN VALENTIN STENGER.
